LOOSE LEAF BINDER

Marshall I. Williamson, Edgewater, N. J.

Application August 16, 1935, Serial No. 36,470

3 Claims. (Cl. 129—41)

My invention relates to improved loose-leaf binders and the assembly therein of a stack of optional number of leaves.

One aspect of my invention pertains to an enclosing member, which may serve also as the cover, formed of pliable material, suitably contoured to provide for front and rear cover portions, the stack of leaves of desired number being positioned within and attached to the stated enclosing and/or cover member by one or more tongue elements which may be blanked from the material of the enclosing and/or cover member.

The enclosing and/or cover member may be of genuine leather or of so-called imitation leathers, or may be of metal possessing suitable pliability, other material having the required attributes, as later appears, may be employed.

Embodiments of my invention may have a single tongue element, or if preferred, two or more tongue elements, the stack of loose leaves being provided with registering openings, recesses, apertures, slots, or the like, in correspondence to the position or positions of such one or more tongue elements, to afford the insertion of the tongue element or elements respectively therethrough. The free end of such tongue element or elements is lodged and/or locked in position, by inserting the same through a set of parallelly arranged slits in the portion of the enclosing and/or cover member opposite relative to the portion of the same from which the tongue element is blanked.

In the disclosed embodiments, the opposite lateral edges of the free end of the tongue member have serrations or other irregular or non-rectilinear formations for locking the tongue element.

If desired, the stack of loose leaves may be retained within an enclosing member, desirably of metal and dimensioned to constitute the backbone and preferably to embrace the stack of loose leaves, the enclosing member being secured by stapling, adhesive or in any other suitable manner to a cover which wholly embraces the stack of loose leaves as well as the enclosing member.

Preferably, each loose leaf is contoured at its edge adjacent the backbone of the enclosing or cover member to be spaced at the major portion of such edge from the backbone, as by providing extensions of the paper at the locations of the openings, recesses or the like, through which latter the tongue elements pass. By such arrangement upon opening the binder, the leaves freed substantially from interfriction with one another, 55 open "flat", affording utilization of the whole

area of each page for entries, etc. thereon and visibility of written, printed and other matter thereon.

Further features and objects of the invention will be more fully understood from the following detail description and the accompanying drawing, in which

Fig. 1 is a plan view, partly in horizontal section, of a preferred embodiment of my invention;

Fig. 2 is a sectional view on line 2—2 of Fig. 1; this view also indicates in dot and dash line the movement of a tongue element of the enveloping member in attaching therewith a stack of loose leaves, the stack in this instance comprising a relatively few number of leaves;

Fig. 3 is a view similar to Fig. 2, showing the relative positions of the enclosing member, the attaching tongue element and a stack comprising a relatively large number of loose leaves.

Fig. 4 is a detail sectional view generally similar to Fig. 2, but of another preferred embodiment, illustrating in particular a cover independent of and suitably attached to the enclosing member.

Referring to the accompanying drawing, 10 and 11 indicate the front and rear portions of an enclosing and/or cover member adapted to bind and hold within such member a stack of any optional number of leaves 12; such portions 30 may constitute one sheet with an intervening portion 12a dimensioned to serve as the backbone of the enclosing and/or cover member. Such enclosing or cover member may be of a genuine or of imitation leather, or may be constructed of thin metal or metallic material possessing suitable pliability, or of other material, such as paper, cloth or the like, adapted to the purpose specified.

One portion of the cover member, say the front 40 portion, is blanked or incised to form a tongue of a shape such as that shown at 13. Either one or, if desired, two or more such tongue elements may be provided, such as is illustrated at 13a and 13b, Fig. 1.

The stack of loose leaves to be bound within the said cover is provided with registering openings or recesses one or more in each sheet or leaf as preferred; said openings may be in the form of apertured slots as shown at 14, one purpose 50 thereof being to facilitate insertion or removal of one or more sheets from the stack. Such openings afford attachment of the leaves individually and as a stack by insertion therethrough of the tongue element 13 as is illustrated at 15. 55

The free end of such tongue may be locked in position by insertion, through one or more incised slits as at 16 and/or 16a in that portion of the cover member opposing that from which the tongue is blanked or incised.

For further securement of the free end of the tongue and to position it within the cover member, the free end of the tongue, after such insertion, within one slit, say 16, is also inserted through a second slit 16a, parallel to such first slit 16. Such procedure positions the end of the tongue wholly within the enclosing or cover member, and provides a neat and ready arrangement for accomplishing the purposes of the invention.

It is desirable to also lock the free end of the tongue after it has been thus lodged, and this may be accomplished in various ways.

Such incised slit may have an outline of artistic configuration, in embellishment of the assembly as a whole.

The free end of the tongue is locked preferably by providing the tongue element with a serrated or other non-rectilinear outline, see 18, Fig. 1, at both of its lateral edges, one of said edges to be engaged and locked within the incised slit 16a of the cover member, and the other edges to engage and lock relative to another slit provided therein for that purpose as at 19, Fig. 1.

If desired, the binder may have an outer cover left entire, that is, without blanking therefrom any tongue element, the loose leaves being detachably positioned, as above set forth within an enclosing member which may be of metal or the like, from which enclosing member the herein described tongue element or elements are blanked, one form of which is illustrated in Fig. 4. Such inner member 10, 11 may be dimensioned less than its cover 21. Such inner member 10, 11 may be formed as a channel to constitute the backbone and to directly embrace the stack of loose leaves, and is secured to the outer cover member by adhesive or by stapling, eyeletting, etc., as indicated at 22.

It will be understood that in such arrangement the lesser dimensions of the inner member 10, 11 are satisfied by providing sufficient material for the formation of the tongue element and the incised slits 16 and 16a, through which it is to be inserted, lodged and locked, similarly as previously described.

The preferred form of loose leaf, as illustrated in the drawings, has its inner edge, see edge portion 12b, Figs. 1 and 4, spaced from the inner face of the backbone of the enclosing member 10, 11, as by providing the extensions 12c, encompassing each apertured slot 14, recess or the like, such spaced edge portion 12b between such extensions constituting the major part of the whole inner edge of each sheet, whereby upon opening the binder, the friction of the leaves relative to one another at their stated inner edges is negligible as compared with the effect afforded by the stated spacing of the major edge portions 12b from the backbone—and when so opened from all portions of the enclosing member 10, 11.

In the use of a serrated or other non-rectilinear outline, see 18, Fig. 1, for the lateral edges of

each tongue element, say tongue element 13a, Fig. 1, it is advantageous to extend a locking slit, say slit 16a, as indicated at 16a', to have a length of the slit opening appreciably greater than the lateral dimension of the tongue element, such extended length portion 16a' being offset from alignment with the tongue at that side of the latter adjacent the arcuate locking slit 19. The tongue element may therefore be easily slipped through the slit 16a and may be finally brought into locked position, the serrations of its opposite lateral edges engaging, respectively, the end of slit 16a, which is opposite the extended end 16a' thereof, and slit 19.

Whereas I have described my invention by reference to specific forms thereof, it will be understood that many changes and modifications may be made without departing from the spirit of the invention.

I claim:

1. In a binder for a stack of loose leaves, a cover element having a flexible leaf-engaging tongue integrally extending therefrom, said tongue having serrated lateral edges; a pair of slits in said cover element spaced apart mutually and spaced backwardly from the base of said tongue, the individual slits of said pair of slits and the base of said tongue being substantially mutually aligned in parallel relation, whereby the tip of said tongue may be passed through that individual slit which is proximate its base, and thereafter through the other individual slit of the pair of slits in securing the stack of loose leaves within the cover element; and means provided in the cover element for engaging one lateral edge of the free end of the tongue in maintaining the serrations of the other lateral edge of the tongue in locked relation with one end of at least the said other individual slit of the said pair of slits.

2. Structure as recited in claim 1, wherein the stated other individual slit is longer than the individual slit which is proximate the base of the tongue and is slightly offset lengthwise from the latter, and wherein the stated means for engaging one lateral edge of the tongue is a substantially arcuate slit farther removed from the base of the tongue than is the stated pair of slits and extending at substantially right angles to the lengths of the individual slits of the latter, the said substantially arcuate slit being offset inwardly from that end of said longer individual slit which extends beyond the other individual slit of the pair of slits, and, further, having its convexity directed inwardly.

3. In a binder for a stack of loose leaves, a cover element having at least one flexible leaf-engaging tongue extending therefrom, said tongue having serrated lateral edges; a slit adapted to receive said tongue after engagement with said stack of loose leaves, said slit having a length greater than the width of said tongue; and means for forcing one lateral edge of the tongue into locking engagement with one end of the said slit, said means being adapted to engage the other lateral edge of the tongue to maintain said tongue in locked status relative to the stack of loose leaves.

MARSHALL I. WILLIAMSON.
